SOLID COLOR PATTERNED STOCKING WITH SPLIT FOOT

Richard B. Kale and Norman J. Lemons, Mebane, N.C.,
assignors to Kale Knitting Mills, Inc., Mebane, N.C., a
corporation of North Carolina

Filed Nov. 25, 1957, Ser. No. 692,776
3 Claims. (Cl. 66—179)

This invention relates to stockings of the so-called solid color pattern type having reciprocatory pattern areas in the form of diamonds, gussets or other shapes, each of which is knit of a different yarn than that of which adjacent or contiguous areas are knit and in which each patterned area is joined to contiguous areas by true sutures.

It is an object of this invention to provide a stocking of the character described, and a method of making the same, wherein the stocking is provided with a split foot with the heel and sole being knit from a different yarn from that of which the instep area is knit and wherein the latter areas are also knit from different yarns from that of which any of the pattern areas in the leg of the stocking are knit.

It is another object of this invention to provide an Argyle stocking of the solid color pattern type and a method of making the same in which the stocking is so constructed that the heel, sole and toe portions of the stocking may be knit from a relatively heavy yarn as compared to that from which the instep and leg portions of the stocking are knit to provide a cushion sole, for example, without the necessity of floating the heavy yarn across the instep of the stocking, as has been necessary heretofore.

To our knowledge, prior to the present invention, no means had been developed in which instep and foot areas could be knitted reciprocatorily following the knitting of reciprocatorily knit pattern areas in the leg of a stocking, because no means had been discovered for satisfactorily anchoring incoming and outgoing yarns at the juncture of the solid color pattern areas in the leg with the heel and instep portions of the stocking, or at the juncture of the sole and instep portions with the ring toe of the stocking. Such discovery has been lacking due to the peculiarities involved in the knitting of contiguous areas at different knitting stations.

In U.S. Patent No. 2,217,022, there is described a machine for knitting solid color patterned hosiery fabric, wherein two knitting stations are employed with the cylinder reciprocating to and fro so that the needles knit contiguous patterns with separate yarns at different knitting stations, and the patterns are joined together by interknitting loops of adjacent pattern yarns.

In the knitting of the present fabric, two diametrically opposed substantially triangularly-shaped pattern areas or substantially flat-bottom gussets are knit at opposite sides of the bottom portion of the leg of the stocking at a main knitting station and the lower pointed portions of diamonds are knit between the latter gussets at the front and rear of the stocking at an auxiliary knitting station. The proximal edges of adjacent areas are interconnected by sutures which extend at an angle to the wales and courses of the fabric.

In order to anchor the yarns in the fabric and avoid creating holes in the fabric at the juncture of the leg and instep portions of the stockings, the instep yarn is introduced and knit in a course at the bottom of the front diamond at the auxiliary station and the yarn from the final course in one of the side gussets is taken in the hooks of a few needles without being knit at the main knitting station and is subsequently knit with the instep

2

yarn with these few needles at the auxiliary station. Knitting continues with the instep yarn at the same course while the yarn from the latter gusset is floated inside the fabric past a plurality of stitches of the instep yarn and to the point of the heel pocket. At the latter point, an additional yarn, which will be termed as a sole yarn (although it is used in knitting the heel, sole and the toe of the stocking), is introduced and knit with the latter gusset yarn independently of the instep to complete the

- 10 final course in the latter gusset, the yarn from the latter gusset being withdrawn at the point of the rear diamond and knitting continuing with the sole yarn only at the main knitting station to thereby complete the first course in the heel. This anchors the instep and sole yarns into the fabric so that the instep may subsequently be knit in juxtaposition to the terminal portions of adjacent pattern areas in the leg and from a different yarn from that of which the heel and sole of the stocking are knit during reciprocating knitting.
- 15 20 The instep yarn is anchored to the fabric upon going into rotary knitting of the ring toe courses in a similar manner.

Some of the objects of the invention having been stated, other objects will appear as the description proceeds when taken in connection with the accompanying drawings in which—

FIGURES 1 and 2 are elevations of opposite sides of a stocking knit according to the present invention;

FIGURE 3 is a front elevation of the stocking;

- 30 FIGURE 4 is a greatly enlarged fragmentary inside view of substantially the part of the stocking defined in dash-and-dot lines in FIGURE 3, and showing the novel manner in which the instep and sole yarns are tied to the reciprocatorily knit pattern areas in the leg of the

- 35 stocking;
- FIGURE 5 is a schematic inside view of the stocking as though it has been split along certain of its sutures, but omitting the toe pocket and with brackets indicating the overlapping and floating portions of different yarns;

- 40 FIGURE 6 is a diagrammatic view showing the needle cams, jack cams and selector plungers of a machine of the type disclosed in U.S. Patent No. 2,217,022;

FIGURES 7 through 12 are diagrammatic plan views showing some of the needles, some of the yarn guides and the yarns being fed, with the needles occupying various positions with successive steps in movement thereof in the directions indicated by the arrows;

- 45 FIGURES 13 and 14 are views similar to FIGURES 7 through 12, but showing successive positions occupied by the needles and associated elements upon completion of the knitting of the instep.

Referring more specifically to the drawings, the stocking shown in FIGURES 1, 2, 3 and 5 comprises a top R, leg L and a split-foot F with a heel H, instep I, sole S, ring toe RT and toe T. The top R is circularly knit in the usual manner, preferably in the form of a rib fabric or plain fabric having elastic thread incorporated therein. The leg L is reciprocatorily knit in substantially the manner disclosed in U.S. Patent Nos. 2,217,022 and 2,302,211 to form independent solid areas, diamonds or gussets with or without a seam along the back of the leg. Since the present invention is only concerned with the portion of the leg L adjacent the foot F, reference numerals will apply only to the front and rear diamonds and the first and second side gussets, which are respectively broadly designated at 50, 50', 52, 52'. The juncture of the side gussets 52, 52' and instep I are defined by dotted lines in FIGURES 1, 2 and 3.

- 60 65 70 The remainder of the stocking, with the exception of the ring toe RT is also reciprocatorily knit so that each of the areas 50, 50', 52, 52' and I is knit of a different

yarn from the immediately adjacent or contiguous area. Although a yarn change could occur in the knitting of the heel H, sole S and toe T, the heel H, sole S and toe T are preferably knit of the same yarn, which yarn is preferably a cushion yarn to provide a cushion sole, heel and toe on the stocking.

As heretofore stated, the invention resides in the novel method of anchoring incoming and outgoing yarns at the bottom of the patterned areas in the leg and at the start or top of the split-foot areas as well as at the juncture of the split foot with the ring toe courses. In order that the novel structure may be clearly understood, pertinent knitting instrumentalities will be described with particular reference to FIGURES 6 through 14. With the exception of a special arrangement of the needle butts, the machine involved in the knitting of the present fabric is of the conventional two feed type substantially as disclosed in said U.S. Patent No. 2,217,022.

As shown in FIGURE 6, the machine is provided with two diametrically opposed knitting stations, namely, a main or first knitting station K and an auxiliary or second knitting station K' which are disposed at the respective right-hand and left-hand sides of the machine when viewed with respect to the needle circle shown in FIGURES 7 through 14. The knitting station K comprises right-hand and left-hand stitch cams 60, 61 and a top center cam 62. Corresponding cam 60', 61' and 62' comprise the auxiliary station K'. The stations K, K' are provided with narrowing picks 100 and widening picks 101, respectively.

As disclosed in said patent, the sets of stitch cams K, K' are independently radially movable according to the desired pattern to render them active and inactive. The auxiliary set of stitch cams K' also includes a wing cam 64 spaced closely above the top center cam 62'. In FIGURE 6, the cams are cut at the center of the auxiliary knitting station K' and, thus, opposite halves of such cams appear at the extreme ends of the FIGURE. The usual raise cams are provided between the main and auxiliary sets of stitch cams K, K', the needle raise cam at the back of the machine being indicated at 65 and the needle raise cam at the front of the machine being indicated at 66. Conventional needle raising switch cams 70, 71 are provided at the front and at the back of the machine. These switch cams 70, 71 are active for engaging the butts of needles during reciprocatory knitting of areas other than the split foot F to effect the usual widening and narrowing operations.

The knitting machine is provided with conventional selector jacks J each of which is provided with a plurality of saw-tooth removable butts 74, a master butt 75 and an auxiliary or leveling butt 76. Below the stitch cams are conventional jack leveling or lowering cams 80, 80' and circularly spaced series of pattern controlled selector plungers 81, 82, 81' and 82'. The needle cams are supported on a conventional needle cam supporting plate 83 which encircles the needle cylinder. A conventional bed plate 84 also encircles the needle cylinder and is spaced beneath the needle cam supporting plate 83. The bed plate 84 has jack raising cams 85, 86, 85' and 86' thereon which serve to engage the master butts 75 of any jacks J selected by the respective series of selector plungers 81, 82, 81' and 82' to raise these jacks and their needles to take yarn from the next succeeding yarn feed finger then in active or lowered position.

Yarn feed stations 90, 90' (FIGURES 7 through 14) are spaced above the respective knitting stations K, K'. The yarn feed fingers at station 90 are indicated at a through g and the yarn feed fingers at station 90' are indicated at a' through g' in FIGURE 7. Some of the yarn feed fingers are omitted from the FIGURES 8 through 14 for purposes of clarity.

Referring to FIGURES 7 through 14, it will be observed that the needles (broadly designated at N) are divided into groups of short butt needles 91 and long butt needles 92, each of which groups includes substantially

half of the needles. At least one medium butt needle is provided between ends of the groups of short and long butt needles 91, 92 these two medium butt needles being indicated at 93 and 94.

In knitting a stocking, all the yarn feed fingers in sets 90 and 90' may be employed. However, since the present invention is concerned only with the split-foot and the lower portion of the leg of the stocking, yarns Y-1, Y-2, Y-3, Y-4, Y-5 and Y-6 are shown extending from the respective yarn feed fingers b, c, d, a', b' and c' in the pertinent FIGURES 7 through 14. It will be observed in FIGURES 4 and 5 that the yarns Y-1, Y-3, Y-5 and Y-6 are knit in the respective leg pattern areas 52', 52, 50 and 50'. Only the yarn tails appear in FIGURE 5. The yarn Y-2 is knit in the heel H, sole S and toe T and will be termed as a sole yarn. The yarn Y-4 is knit in the instep area I.

Referring to FIGURE 4, the knitting progresses from the top toward the bottom in this figure and the courses are marked by arrows indicating the direction in which they are knitted. The needle wales are indicated at W-1 through W-21. The partial courses shown in gusset 52 are indicated at C-1 through C-4, and the partial courses in gusset 52' are indicated at C-1', C-2' and C-3'. Those split-foot courses in FIGURE 4 are indicated at C-5, C-6 and C-7. It is apparent that a substantial number of wales are present between wales W-4 and W-5, W-16 and W-17, and W-1 and W-21 respectively. It is apparent from the foregoing description that the diamond area 50 in the central portions of FIGURES 4 and 5 and the diamond area 50' in the right-hand central portion of FIGURE 5 are knit at the auxiliary knitting station K' while the intervening gusset areas 52 and 52' are knit at the main station K with true sutures being formed at the junctures of the latter area in a manner fully described in U.S. Patent No. 2,217,022. Accordingly, only partial courses involved in the knitting of the lowermost portions of the gussets 52, 52' and the diamond 50 will be described.

Those courses knitted from left to right in FIGURE 4, as indicated by the arrows, are knit with clockwise movement of the needle cylinder in FIGURES 7 through 14, and those courses which are knit from right to left in FIGURE 4 are knit with counterclockwise movement of the needle cylinder. Comparing the partial courses C-3, C-2' of gussets 52, 52' and a course P of diamond 50 in FIGURE 4 with FIGURE 7, it should be noted that the partial course C-2' is knit with counterclockwise movement of the needle cylinder. The extreme left-hand loop (wale W-14) in this partial course C-2' is held on the corresponding needle while the penultimate partial course P in the bottom of the diamond 50 is subsequently being formed at the auxiliary knitting station K' and during the next clockwise movement of the needle cylinder. Thus, with the stocking and needles in the position shown in FIGURE 7, the extreme right-hand loop in course P, wale 14, of the diamond 50 is not formed until after the final course in the gusset 52' (FIGURE 4) is completed, at the completion of which the yarn feed finger b is withdrawn from action.

With continued clockwise movement of the needle cylinder, the partial course C-3 is then knit from left to right in FIGURE 4 so the last three stitches at the right-hand end of the partial course C-3 are pulled through the previously formed first three stitches at the left-hand end of the partial course P. Counterclockwise movement of the needles N then commences and, since the extreme right-hand stitch or loop in the partial course C-3 of the gusset 52 has already been formed and is being held on the corresponding needle, the main set of stitch cams K is partially withdrawn to where only medium and long butt needles will engage cams 60, 61. However, during the withdrawal of the main set of stitch cams K (see FIGURE 8) a leading few selected needles (bracketed at N-1) moving counterclockwise with the needle cylinder,

engage the right-hand stitch cam 60 before it is completely withdrawn so these few needles, which are shown as being three in this instance, take the left-hand side gusset yarn Y-3 in the hooks thereof, but do not draw stitches because the stitch cam 61 is withdrawn before the latter needles N-1 reach the same with movement thereof from right to left in FIGURE 6. The subsequent short butt needles, although selected, are not raised high enough to take yarn Y-3 from finger d. It should be noted that the remaining subsequent short butt needles 91 are thus selected at the main station K for subsequently drawing stitches at the auxiliary station K', as will be later explained.

It will be observed in FIGURES 8 and 9 that after the short butt needles 91 pass the main yarn knitting station K, disposed beneath the yarn feed station 90, the medium butt needle 93 and then the long butt needles 92 are selected at the group of selector fingers 82 and caused to ride up the right-hand stitch cam 60 so that stitches are then drawn with the yarn Y-3, since the set of stitch cams K is only withdrawn sufficiently to miss the butts of short butt needles. Thus, referring to FIGURE 4, it will be observed that the yarn Y-3 is floated from wale W-7 to wale W-3, which wale W-3 is formed by the medium butt needles 93. This portion of the stocking is bracketed at B-5 in FIGURE 5.

As the short butt needles 91, between the needles N-1 and the medium butt needle 93, pass beneath the main set of yarn feed fingers 90, yarn feed finger c (which feeds the sole yarn Y-2) is lowered to operative position (FIGURE 9), the yarn feed finger d having previously occupied lowered position during the knitting of the first side gusset 52. Thus, at the wale W-3 the sole yarn Y-2 is introduced to needle 93 and subsequent long butt needles 92 so that both the yarns Y-2 and Y-3 are knit together in partial course C-4 in the rear half of the gusset 52 (see bracketed zone B-4 in FIGURE 5), at which point the yarn feed finger d, and yarn Y-3, are withdrawn as shown in the successive steps of FIGURES 10 and 11.

As the needles N move counterclockwise from the position of FIGURE 9 to that of FIGURE 10 (while floating yarn Y-3 and then knitting yarns Y-2, Y-3 together at knitting station K), yarn feed finger a' (which feeds the instep yarn Y-4) moves into active position and three needles (in this instance) N-2 are selected by selector plungers 82'. The latter needles N-2 are immediately adjacent the needles N-1. With further counterclockwise movement of the needles N, the bottom portion of the front diamond 50 moves in the vertical plane of the auxiliary knitting station K' and the auxiliary set of yarn feed fingers 90' so that the selected short butt needles in group N-2, corresponding to wales W-13, W-12, W-11 in FIGURE 4, receive instep yarn Y-4 from the auxiliary yarn feed finger a' and knit this yarn in partial course Q in plating relation with the yarn Y-5 in the next few wales, which are shown as three wales in FIGURE 4 (see bracket area B-2 in FIGURE 5). Thereupon, the yarn feed finger b' is withdrawn (see FIGURE 11) at the auxiliary set of fingers 90' to complete the diamond 50 whereby the instep yarn Y-4 is securely anchored in the course portion Q.

With continued counterclockwise movement of the needle cylinder, those needles N-1, in whose hooks the yarn Y-3 had previously been taken from finger d at the main yarn feed station 90 (see FIGURE 8), and which are already in raised position, take the instep yarn Y-4 in the hooks thereof. Thus, stitches are formed both from the yarn Y-3 and the instep yarn Y-4 at the auxiliary knitting station K' in wales W-8, W-9 and W-10 of partial course V (see bracketed area B-1 in FIGURE 5). The course portion V (area B-5, FIGURE 5) is then completed from right to left in FIGURE 4 at the auxiliary knitting station K' on the corresponding short butt needles 91 only (which were previously selected ahead of the main knitting station K), and it will be

noted that the final stitch (wale W-3) at the left-hand end of the partial course V is formed on the medium butt needle 93 (FIGURE 12). The auxiliary stitch cams K' are withdrawn from action and the heel H of the stocking is then formed from the heel yarn Y-5 in the usual manner by the usual narrowing and widening operations in reciprocatory knitting, during which the medium butt needle 93 continues to hold the corresponding stitch thereon. It should be noted that all the intervening stitches then held on the short butt needles, which are those embraced by the wales W-3 and W-15 in FIGURE 4, as well as the stitches of course C-3' in wales W-16 through W-19 are held in the hooks of the short butt needles 91 during the knitting of the heel H (see FIGURE 12).

The sutures and lower portion of the heel H are omitted from the portion of fabric shown in FIGURE 4 so as to clarify the stitch construction of other parts of the fabric, since it is apparent that the stitches in the heel H would actually be distorted in the blank areas in the opposite lower corner portions of FIGURE 4. Since the heel is knit in a conventional manner, a detailed illustration and description of the fabric and the manner in which it is knit is deemed unnecessary.

Upon completion of the knitting of the heel H, the auxiliary knitting cams K' return to fully operative position and the machine continues reciprocatory knitting, but in this instance, the instep yarn Y-4 is knit on all the short butt needles 91 and the sole yarn Y-2 is knit on all the long butt needles 92. On the other hand, the medium butt needles 93 and 94 alternate in knitting with the two yarns Y-2 and Y-4 to form a suture at each side of the stocking along wales W-3 and W-19 at the juncture of the sole and the instep portions thereof (see FIGURES 4 and 13). Since the knitting of split foot fabric is, in itself, well known, a detailed description thereof is deemed unnecessary, the primary feature of the present invention residing in the fact that yarn, from a portion of which stitches were made at the main yarn knitting station K, is interknit in a contiguous course with other yarn from which stitches are made at the auxiliary knitting station K'.

During knitting of the heel H the auxiliary knitting cams K' are withdrawn. However, during reciprocatory knitting of the instep I and sole S, the auxiliary knitting cams K' occupy active position. It is apparent, therefore, that, whereas the long butt needles 92 are raised to pass through the knitting station K by alternating active or inward and then outward movements of the switch cams 70, 71 (FIGURE 6) in knitting the sole S (narrowing picks 100 and widening picks 101 then being inactive), selector plungers 81, 82' are alternately controlled to raise the jacks J and corresponding short butt needles 91 to pass through the knitting station K' to knit in the instep I.

As heretofore stated, the yarn change at the final course in the instep, and immediately preceding the knitting of the ring toe RT is effected in a manner similar to that in which the yarn changes are effected at the juncture of the leg and the instep of the stocking. Referring to FIGURE 13, it will be noted that both of the yarn feed fingers a' and c occupy lowered or operative position and the respective yarns Y-4 and Y-2 are being fed to selected needles. In order to lay the yarn Y-4 in the hooks of some of the short butt needles without knitting the same, the left-hand auxiliary stitch cam 61' (FIGURE 6) is withdrawn out of action while the right-hand auxiliary stitch cam 60' remains in action for a sufficient length of time to raise a sufficient number of needles to insure that the yarn will subsequently be securely anchored in the fabric at the juncture at the instep with the ring toe. In this instance, approximately twenty short butt needles 91 are raised by the right-hand auxiliary stitch cam 60' after the left-hand auxiliary

stitch cam 61' has been withdrawn from action. These twenty needles are bracketed at N-3 in FIGURE 14.

Said twenty short butt needles N-3 are preferably located substantially midway between the medium butt needles 93 and 94 and have the yarn Y-4 laying in the hooks thereof in FIGURE 14. The latter needles N-3 remain elevated after passing the auxiliary knitting station K'. The yarn feed finger a' is raised out of action and the right-hand auxiliary stitch cam 60' is also withdrawn from action as the last needle in group N-3 moves past the same. Thus, the yarn Y-4 is held in the hooks of the group of needles N-3. The preceding short butt needles 91 to the right of the group N-3 in FIGURE 14, will have already drawn stitches at the auxiliary knitting station K' and, as the long butt needles 92 pass the main knitting station K, the main knitting station K moves into fully operative position so as to not only raise the long butt needles 92 to take the sole yarn Y-2 and draw stitches therewith, but to also raise all the remaining needles, including the subsequent short butt needles 91.

It is apparent that, as the short butt needles 91 are raised and take the yarn Y-2 in the hooks thereof, they are subsequently lowered by the left-hand stitch cam 61 at the main station K to form stitches therewith. Thus, those needles N-3 in whose hooks the yarn Y-4 had originally been taken at the auxiliary knitting station K' will take the yarn Y-2 from yarn feed finger c at the main station K and subsequently draw stitches from both the yarn Y-2 and the yarn Y-4 to securely anchor the latter yarns together (see area B-3, FIGURE 5). The needle cylinder then continues counterclockwise rotation to complete the knitting of the ring courses, whereupon the machine goes into reciprocatory knitting to knit the toe T, as is usual.

It is thus seen that we have provided a novel method of anchoring incoming and outgoing yarns in circular knit fabric on a two-feed or multi-feed machine in which yarn which is being knit at one station is taken in the hooks of a few needles and is not knit at the particular station and the latter portion of yarn is subsequently knit with yarn from the other of the two stations, or at a subsequent knitting station, to thereby securely anchor the two yarns in the fabric.

In the drawings, and specification there has been set forth a preferred embodiment of the invention and, although specific terms are employed, they are used in a generic and descriptive sense only and not for purposes of limitation, the scope of the invention being defined in the claims.

We claim:

1. A stocking having a leg knitted in the form of solid colored patterned areas in which adjacent areas are interconnected by knitted sutures, said stocking having a split foot including an instep formed from an independent instep yarn and a heel and sole formed from an independent sole yarn, an initial course in the instep having the

incoming instep yarn knitted together with a few stitches formed from at least two adjacent areas of the leg, and the sole yarn also being knit together with a few stitches at the bottom of at least one of said areas of the leg to thereby anchor the instep and sole yarns to the respective areas of the leg.

5 2. A stocking having a leg knitted in the form of solid color patterned areas including front and rear diamonds and intervening first and second side gussets and being connected to the adjacent areas by knitted sutures, a split foot including an instep knit of an instep yarn and a heel and sole knit of a sole yarn independently of the instep yarn with the heel and sole connected to the opposite sides of the instep by knitted sutures, said instep 10 yarn being introduced by being interknitted with and in the same course and wales as those formed by the yarn present in the lowermost portion of the front diamond and an adjacent portion of one of the side gussets for a few wales, with the yarn from the latter side gusset being floated from said last mentioned few wales to the heel, whereat the yarn from the latter gusset is knitted together with the sole yarn in a plurality of wales forming a pair, at least, of the initial course in the heel to thereby anchor the front diamond and said adjacent gusset to the instep 15 and to also anchor said adjacent gusset to the heel.

25 3. A tubular knit stocking having a reciprocally knit leg including patterned areas, adjacent areas being knit of separate yarns and being interconnected by knitted sutures extending at an angle to the wales and courses of the stocking, the areas at the bottom of the leg being substantially triangular with the point of one of the latter areas terminating in a bottom course of stitches at the front lower portion of the leg, said stocking also comprising a split foot including an instep and a sole each knit of an independent yarn, the yarn in said instep being different from the yarn in said point of said one of the areas, and the first course knit in said instep including stitches knitted in plated relation with stitches of the bottom course in said point.
